Filed Oct. 11, 1960, Ser. No. 61,909

15 Claims. (Cl. 260—672)

This invention relates to a process for the disproportionation of toluene to produce benzene and polymethyl benzene. More particularly, this invention is concerned with a process employing a reaction promoter in the conversion of toluene to benzene and xylene and/or other polymethyl benzenes. It is known in the art that certain alkyl benzenes, other than toluene, can be disproportionated with a BF_3 catalyst in the presence of HF . For example, A. P. Lien et al., U.S. 2,528,893, patented November 7, 1950, discloses a method for the disproportionation of ethyl benzene to diethyl benzene and benzene in good yields. Also, A. P. Lien et al., U.S. 2,564,073, patented August 14, 1951, discloses the disproportionation of xylene to trimethyl benzene in good yields. However, it had previously been thought impossible to disproportionate toluene in good yields until recently. Toluene contains only one alkyl group on the aromatic nucleus and the alkyl group is a methyl group. It is extremely difficult to remove the methyl group from the toluene nucleus and place it on the aromatic nucleus of another toluene molecule by disproportionation.

However, a process has been developed for disproportionating toluene and obtaining good yield of xylene and other polymethyl benzenes without undue destruction of the reaction product by cracking and condensation. The recently developed process uses an $\text{HF}-\text{BF}_3$ catalyst and reaction temperatures of from 80° C . to 125° C . Although good yields of polymethyl benzenes, such as xylene and mesitylene, are obtained from the process, the process is useful on a commercial basis only over a limited temperature range and only with a particular catalyst.

We have now discovered that the disproportionation of toluene to benzene and polymethyl benzene can be carried out over a wider temperature range while using any strong acid Friedel-Crafts catalyst by using certain promoters for the disproportionation reaction. Accordingly, toluene is contacted with a strong acid Friedel-Crafts catalyst at a temperature in the range of from about 0° C . to 125° C . in the presence of a promoter selected from the class consisting of a diarylmethane having mononuclear aryl groups and a polyhalohydrocarbon. The polyhalohydrocarbon which is useable as a promoter has the gem-dihalo structure and corresponds to the following structural formula:

wherein X is a halo group and R and R' are each selected from the class consisting of a halo group, a hydrogen group, an alkyl group and a hydrogen-containing haloalkyl group. The halo groups may be fluoro, chloro, bromo and/or iodo groups. The hydrogen-containing haloalkyl group may advantageously be an open chain (i.e., non-cyclic) alkyl group although it may contain cycloparaffinic or aromatic substituents. The alkyl group and haloalkyl group are preferably saturated. The contacting is carried out for a period of time sufficient to disproportionate toluene to the desired polymethylbenzene, and the polymethylbenzene is then separated from

2

the reacted mixture as a disproportionation product. Benzene may also be separated as a product if desired. Any remaining unreacted toluene may be recycled to the contacting step.

5 It is preferred that the promoter be readily separable from the desired reaction product, such as by distillation. Therefore, in an advantageous embodiment of this invention, the promoter boils outside the boiling range of desired products.

10 The diarylmethane and polyhalohydrocarbon promoters useable in accordance herewith are at least partially soluble in the catalyst phase or in the toluene phase or both phases under the reaction conditions. Complete solubility is desirable for greater promoter activity but is not necessary. Where the promoters are referred to herein as being soluble or partially soluble, it is fully intended that they may be only very slightly soluble so long as they possess some solubility in the reaction system.

15 The diarylmethanes are those diarylmethanes wherein the aryl groups are mononuclear aromatic groups and are capable of splitting off a phenyl nucleus (including alkyl substituted phenyl nuclei) and a benzyl ion (including alkyl substituted benzyl ions). Thus, any diarylmethane wherein the aryl group is a benzene group or an alkylbenzene group is useful. Specific examples of such diarylmethanes are ditoluomethane, diphenylmethane, dixylomethane, dimesitylmethane, ethylphenyltoluomethane, di(ethylphenyl)methane, di(octylphenyl)methane, di(butylphenyl)methane, eicosphenyltoluomethane, di(octyldecylphenyl)methane, hexadecylphenyltoluomethane, and the like. Diphenylmethane is particularly preferred.

20 25 30 35 The polyhalohydrocarbons useable as promoters have been defined with reference to the above formula. From the formula, it is evident that the polyhalohydrocarbon promoters must contain at least two halogen groups on the same carbon atoms, i.e. a gem-dihalo structure. It is also evident that, although the term polyhalohydrocarbon is used in the general description of the compound within the formula, it is not necessary that hydrogen be present in the compound where there is only one carbon atom in the formula. Thus, such compounds as carbon tetrachloride, carbon tetrabromide, carbon tetrafluoride, and the Freons are useable. The Freons include Freon 11 (CCl_3F), Freon 12 (CCl_2F_2) and Freon 13 (CClF_3). However, with reference to the structural formula, where more than one carbon atom is present the promoter is not a perhalo compound, i.e. it contains 40 45 50 55 hydrogen linked to a carbon atom.

60 65 70 The polyhalohydrocarbon may be of any molecular weight desired. The polyhalohydrocarbon is preferably a saturated open chain polyhalohydrocarbon of any chain length desired with respect to the solubility or partial solubility in the reactants as disclosed above. The polyhalohydrocarbon may have as many halogen groups and/or gem-dihalo structures as desired so long as it has at least one gem-dihalo structure and, where the polyhalohydrocarbon has more than one carbon atom, at least one hydrogen group as described above. The preferred halogen of the gem-dihalo structure is chlorine.

75 Typical examples of other specific useable polyhalohydrocarbons are

- 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

 3,3,6-trichlorohexadiene-1,4;
 hexadecyldecachloride, etc.

Also useable are the halogenated hydrocarbons such as halogenated waxes and halogenated hydrocarbon polymers, e.g. chlorinated paraffin waxes, such as those containing from 30 to 70 weight percent chlorine and marketed under such trade names as Aroclor (Monsanto Chemical Co.); Chlorowax 40 and 70 (Diamond Alkali Co.); Clorafin 42 and 70 (Hercules Powder Co.); CP-40 (Hooker Electrochemical Co.); Halowax (Union Carbide & Carbon Corp.); Paroil (Amoco Chemicals, Inc.), etc., chlorinated polyisobutylene; chlorinated polyethylene; chlorinated polybutene; fluorinated polypropylene; brominated polyethylene; chlorinated copolymers of isobutylene and styrene; iodinated copolymers of ethylene and propylene; iodinated polyisobutylene; brominated paraffin wax; fluorinated olefin waxes, etc. Further, the polyhalohydrocarbon may be a chlorine-containing polymer such as polyvinylidenechloride. Examples of additional useable promoters are 1,1,1-trichloro-2-phenylethane; 1-naphthyl-12,12-dibromododecane; chlorinated hydrocarbon petroleum fractions such as the chlorinated naphthalenes, and the like. Other polyhalohydrocarbons falling within the above definition are well known to those skilled in the art and any such compositions may be used. Where it is desired to use a viscous polyhalohydrocarbon, it may be particularly desirable to mix the viscous polyhalohydrocarbon with a low molecular weight polyhalohydrocarbon which functions not only as an additional promoter but also as a solvent for the more viscous material. The polyhalohydrocarbon is soluble in toluene or the catalyst phase or may be rendered soluble in toluene or the catalyst phase by solvents.

The contacting is carried out at a temperature in the range of from 0° C. to about 125° C. More advantageously, the contacting temperature is lower than about 100° C., because above 100° C. advantageous commercial processing may be obtained using the HF-BF₃ catalyst in accordance with the method of D. A. McCaulay described in copending application Serial No. 51,223. The reaction temperature also depends upon the particular promoter used. Accordingly, where the polyhalohydrocarbon is used as a promoter, it may be advantageous to use temperatures in the range of from 50 to 100° C. and, preferably 65 to 100° C. Where a diarylmethane is used as the promoter, the preferred temperature range is 20 to 75° C. The contacting is carried out for a period of time sufficient to produce the desired product. Usually from about 15 minutes to about 5 hours may be required. However, at lower temperatures the reaction times will be longer and conversely at higher reaction temperatures less reaction time will be required. The reaction time should be related to reaction temperature and catalyst to obtain the desired conversion to the desired product and to minimize side reactions. The promoter used will affect reaction times and suitable reaction time can readily be determined by simple experimentation within the skill of the art.

The reaction in the presence of the catalyst is believed to be promoted by the presence of either the gem-dihalo carbon group or the phenyl nucleus and benzyl ion when utilizing the promoters of this invention.

The strong acid Friedel-Crafts catalysts are well known to the art and any such catalyst may be used in the present reaction. Particularly advantageous catalysts are those very strong acid Friedel-Crafts catalysts such as HF-BF₃; AlCl₃-HCl; AlBr₃-HBr, and the like. The catalyst is used in a catalytically effective amount. Advantageously, the amount of catalyst employed may be in the range of from about 0.1 to about 3.0 parts by weight of catalyst per part by weight of toluene. Where the catalyst includes an additional promoter such as HF; HCl, and HBr, the hydrogen halide should also be used in an amount from about 0.1 to about 3.0 parts by weight per part of toluene. Of course, the amount of catalyst used will depend somewhat upon the nature of the catalyst. For example, where HF-BF₃ is used, it is advantageous to employ at least about 0.3 weight percent of each of HF and BF₃. As another example, where an aluminum halide-hydrogen halide catalyst is employed, the amount used for an equivalent amount of disproportionation may be at little as 0.1 weight percent of each of the aluminum halide and hydrogen halide. It is particularly preferred that at least 0.5 weight percent of the catalyst be used for efficient commercial operation. HF-BF₃ is the preferred catalyst.

In the process of this invention, the contacting in the presence of the strong acid Friedel-Crafts catalyst and promoter may be carried out at any pressure normally used for the particular catalyst system. Where a catalyst system containing a hydrogen halide is used, it is normally advantageous to carry the contacting out while maintaining hydrogen halide in liquid phase. Where HCl or HBr are used in the catalyst system, the hydrogenhalide may advantageously be dissolved in the reactants, e.g. in the toluene, and additional pressure is not necessary. HCl or HBr may also be present in the gaseous state as undissolved gas. However, where HF-BF₃, the preferred catalyst system, is used, the contacting must be carried out under pressures sufficient to maintain the HF in the liquid state.

After contacting, the product may be fractionated to provide benzene and polymethylbenzenes which are removed from the system. Fractionation of the product may also yield unconverted toluene which may be recycled to the contacting step. The catalyst may be removed during fractionation and recycled and reused. The polyhalohydrocarbon or diarylmethane promoter may also be separated by fractionation and recycled to the contact-

ing step. Fractionation of the product or effluent from the contacting step may conveniently be accomplished by distillation whereby separate benzene, toluene and polymethylbenzene fractions are recovered. Any hydrogen halide promoter may be recovered as overhead from the distillation, as may BF_3 when BF_3 is contained in the catalyst system. The lower molecular weight polyhalohydrocarbon promoters may be recovered as a low-boiling fraction from the distillation and recycled while the diarylmethane or high-boiling polyhalohydrocarbons and catalysts other than BF_3 may be recovered and recycled as bottoms from distillation.

The polymethylbenzene recovered as product from the system may conveniently be preselected. Increased reaction temperatures and reaction times are then used to yield a polymethylbenzene having a greater number of polymethyl groups. For example, lower contacting temperatures and contacting times are used for production of a product predominating in xylene than are used, other conditions being constant, for the production of mesitylene. More highly methylated benzenes such as durene and pentamethylbenzene may also be produced at still longer reaction times and/or higher temperatures. However, care should be taken not to exceed 125° C. as a reaction temperature because of the tendency toward product condensation and formation of tars at such higher temperatures.

FIGURE I is a flow diagram illustrating the operation of one embodiment of this invention. FIGURE II is a semi-log plot of conversion against reaction time using various promoters in accordance herewith.

Now turning to FIGURE I, toluene is charged through

covered through line 21 and charged to fractionator 22. In fractionator 22, the stripped bottoms are distilled to obtain a light benzene reaction through line 23, an intermediate toluene fraction through line 24, an intermediate 5 xylene fraction through line 25, an intermediate mesitylene fraction through line 27 and a bottoms fraction through line 28. The benzene reaction recovered through line 23 is a high-purity product and may be removed from the system. The toluene fraction is recycled through line 24 to line 13 and commingled with additional toluene charged through contactor 17. The xylene and mesitylene fractions are recovered as separate products. The bottoms fraction contains diphenylmethane and polymethylbenzenes heavier than mesitylene and may be either recycled through line 24 or removed from the system through valved line 30. The bottoms fraction recovered through line 28 may also contain condensation products of diphenylmethane which may be recycled to contactor 17 and may provide additional promotion of the disproportionation reaction within contactor 17.

EXAMPLES

In order to further illustrate the process of this invention, various disproportionation runs were made using 25 promoters within the scope of this invention in the disproportionation of toluene. The promoter used, amount of promoter, amount of toluene, amount of catalyst, and conditions of reaction are set out in the following table. At intermittent reaction times identified in the table, 30 portions of the reactants were removed and analyzed with the product composition results reported in the table. The conditions and results were as follows:

Table

² HF maintained in liquid state.

line 13 to contactor 17. Contactor 17 is a contacting vessel equipped with an agitator. BF_3 ; HF and diphenylmethane are charged to line 13 by way of valved lines 11, 12, and 14 respectively. The catalyst and promoter are then charged to contactor 17 and agitated with the toluene at a temperature of about 50° C. for a period of about three hours. The concentration of diphenylmethane is about 5% based on toluene and the amount of each of BF_3 and HF charged is about two pounds per pound of toluene. After three hours of contacting, the contents of contactor 17 are removed through line 18 and charged to stripping tower 20. The stripping tower is operated just below the benzene boiling point and HF and BF_3 along with some benzene are taken overhead through line 31, cooled in condenser 32 and charged to settler-separator 33. In settler-separator 33, benzene and HF are recovered in the liquid state, through lines 34 and 37 respectively. The recovered benzene is a high-purity benzene product. The liquid HF is recycled through line 37 to line 35 and may be recharged through line 13 to contactor 17. BF_3 is taken as a gaseous overhead from settler-separator 33 and recycled through line 35 and 13 to contactor 17.

The bottoms fraction from stripping tower 20 is re-

55 With reference to the data reported above in the table, it is seen that the diphenylmethane, trichloroethane and carbon tetrachloride were effective promoters in the disproportionation reaction. By comparing the results of runs 1 and 2, it is seen that the diphenylmethane markedly increased the amount of disproportionation in a given length of time. The same is true for the trichloroethane and carbon tetrachloride, i.e. by comparing the results of runs 3 and 5 with the results of run 4.

60 Now with reference to FIGURE II, FIGURE II is a semi-log plot of conversion against reaction time. Diphenylmethane, at room temperature, gives an initial 500-fold increase in rate and, although the rate decreases after about 15% conversion, the conversion is still about 15 times higher than the unpromoted disproportionation (too slow to be represented by a curve on the graph). Also with reference to FIGURE II, at 65° C. carbon tetrachloride and trichloroethane gave a 5-fold and 3-fold increase respectively in rate over the unpromoted reaction (plotted at 65° C. as a dotted line).

65 It is evident from the foregoing that we have provided a promoted disproportionation process which gives increased conversion of toluene to benzene and polymethylbenzenes by utilizing a promoter as herein defined.

We claim:

1. A process for the disproportionation of toluene to produce benzene and a polymethylbenzene, which process comprises contacting toluene at a temperature in the range of from about 0° C. to about 125° C. with a catalytic amount of a strong acid Friedel-Crafts catalyst in the presence of a disproportionation promoter selected from the class consisting of a diarylmethane having mononuclear aryl groups and a polyhalohydrocarbon having a gem-dihalo structure and defined by the formula:

wherein X is a halogen group and R and R' are each selected from the class consisting of a halogen group, a hydrogen group, an alkyl group, and a hydrogen-containing haloalkyl group, said contacting being for a period of time sufficient to disproportionate toluene into said benzene and polymethylbenzene, and separating said polymethylbenzene as a disproportionation product.

2. The process of claim 1 wherein said disproportionation promoter is present in the reaction mixture in an amount of from about one to about 10% by weight based on said toluene.

3. The process of claim 1 wherein said Friedel-Crafts catalyst is HF-BF₃.

4. The process of claim 3 wherein said catalytic amount is from about 0.3 to about 3.0 parts BF₃ and from about 0.2 to about 3.0 parts HF per part by weight of the toluene to be disproportionated.

5. The process of claim 1 wherein the contacting temperature is in the range of from about 0 to about 100° C.

6. The process of claim 1 wherein X is a chlorine group.

7. The process of claim 1 wherein said disproportionation promoter is a saturated open chain polyhalohydrocarbon boiling outside the benzene to said polymethylbenzene boiling range.

8. The process of claim 7 wherein said promoter is carbon tetrachloride and the contacting temperature is in the range of from about 50 to about 100° C.

9. The process of claim 7 wherein said disproportionation promoter is trichloroethane and the contacting temperature is in the range of from about 50 to about 100° C.

10. The process of claim 1 wherein said disproportionation promoter is a diarylmethane boiling above mesitylene.

11. The process of claim 10 wherein said promoter is diphenylmethane and the contacting temperature is in the range of from about 20 to about 75° C.

12. A process for disproportionating toluene to form benzene and polymethylbenzenes as disproportionation products, which process comprises contacting toluene at a temperature in the range of from about 0 to about 125° C. with a catalytic amount of a strong acid Friedel-Crafts catalyst in the presence of a promoter selected from the class consisting of a diarylmethane having mono-

nuclear aryl groups and a saturated open chain polyhalohydrocarbon defined by the formula:

wherein X is a halogen group and R and R' are each selected from the class consisting of a halogen group, a hydrogen group, a saturated open chain alkyl group and a hydrogen-containing saturated open chain haloalkyl group, said contacting being conducted for a period of time sufficient to disproportionate toluene to benzene and said polymethylbenzene, removing said catalyst from the resulting contacted mixture, recycling said catalyst to said

15 contacting step, recovering benzene and said polymethylbenzene as separate fractions from said contacted mixture, recovering toluene and said disproportionation promoter from said contacted mixture and recycling recovered toluene and promoter to the contacting step.

20 13. A process for the disproportionation of toluene to produce benzene, xylene and mesitylene, which process comprises contacting toluene at a temperature in the range of from about 20° C. to about 75° C. with an HF-BF₃ catalyst and from 1 to 10% diphenylmethane

25 based on said toluene for a period of time sufficient to convert toluene to benzene, xylene and mesitylene, stripping HF and BF₃ from the converted mixture, recycling HF and BF₃ to the contacting step, distilling the stripped converted mixture to obtain a high-purity benzene product cut, a toluene cut, a high purity xylene product cut, a high purity mesitylene product cut, and a bottoms fraction containing diphenylmethane, and recycling said toluene cut and said bottoms fraction to said contacting step.

30 14. A process for the disproportionation of toluene to produce benzene and a polymethylbenzene, which process comprises contacting toluene at a temperature in the range of from about 0° C. to about 125° C. with a catalytic amount of a strong acid Friedel-Crafts catalyst in the presence of a phenyl nucleus and a benzyl ion for a period of time sufficient to disproportionate toluene into said benzene and polymethylbenzene and separating said polymethylbenzene as a disproportionation product.

35 15. A process for the disproportionation of toluene to produce benzene and a polymethylbenzene, which process comprises contacting toluene at a temperature in the range of from about 0° C. to about 125° C. with a catalytic amount of a strong acid Friedel-Crafts catalyst in the presence of a gem-dihalo carbon group attached to two groups each selected from the class consisting of a halogen group, a hydrogen group, an alkyl group and a hydrogen-containing haloalkyl group for a period of time sufficient to disproportionate toluene into said benzene and polymethylbenzene and separating said polymethylbenzene as a disproportionation product.
